UNITED STATES PATENT OFFICE

HYMAN B. SEGAL, OF NEW YORK, N. Y., ASSIGNOR TO SEGAL SAFETY RAZOR CORPORATION, OF NEW YORK, N. Y., A CORPORATION OF NEW YORK

SAFETY RAZOR FRAME

Application filed December 19, 1928. Serial No. 327,005.

This invention relates to improvements in safety razors.

It is a primary object of the invention to provide a safety razor which will hold a removable blade in satisfactory position for shaving and to facilitate the introduction and removal of the blade to and from the holding frame.

It is a further object to provide safety razor holding devices which will permit the outer blade holding plate to be moved bodily toward or from the blade which has been assembled on the guard but retaining the plate against being entirely separated from the frame.

These and other objects will appear more fully from the following description when considered in connection with the drawings in which:

20 Fig. 1 is a vertical sectional view of one form of my invention.

Fig. 2 is an elevational view taken at right angles to Fig. 1, showing the blade holding plate moved to blade removing position.

25 Fig. 3 is an outer face view of the construction shown in Fig. 1.

Fig. 4 is a view similar to Fig. 1 showing a modification of my invention.

30 Fig. 5 is an end elevational view of the same and.

Fig. 6 is a sectional view similar to Fig. 4 showing the blade holding plate moved to open position.

It has been found in razors of the type 35 herein referred to that one great difficulty in the use of the razors is that in the complete separation of the parts forming the blade holding frame it is difficult to properly clean the parts and furthermore there is liability 40 of them being displaced to the inconvenience of the user of the razor. According to my invention the cleaning of the parts is facilitated and at no time during the normal use of the razor are the parts of the blade holding frame 45 entirely separated from one another.

Referring to the details of the drawings and particularly to Figs. 1 to 4 wherein I have shown the first form of my invention, I have shown at 8 a usual shank preferably 50 knurled to afford a better grip and integrally

formed in the present construction with an outer guard 10. The guard 10 is of a usual type and includes the usual comb edge 11 employed in such devices. The outer face of the guard 10 is preferably formed on an arc so 55 that the blade will be flexed when drawn to its shaving position against the guard.

The blade 12 is anchored with respect to the guard 10 by means of lugs 14 formed on the outer face of the guard 10 and projecting 60 outwardly through the blade 12 and through plate 16 referred to below. The interior of the shank 8 is hollow and supplied with the attachment bolt 18 formed with the knurled operating portion 19 and screw-threaded 65 portion 20 for receiving the plate 16. It is preferred to lock the bolt 16 against removal from the shank 8 as by means of the pin 21 fitting in the circular slot 22 of the bolt.

The plate 16 must necessarily move in- 70 wardly and outwardly from the guard 10 in order to permit the removal of the blade from the guard 10 and lugs 14. To this end the plate is formed with side or yoke members 24 which may be integrally formed on 75 the plate 16 and extended rearwardly and inwardly into positions adjacent the shank 8. The inner rearward ends of the members 24 are slotted as at 26 and received over the headed pins 28 so as to permit longitudi- 80 nal and pivotal movement of the plate 16 with respect to the shank 8 and guard 10. As shown in the drawings, the pins 28 are formed on a collar 30 swaged upon the shank 8 although obviously any other form of piv- 85 otal and sliding connection may be employed.

According to the second form of my invention shown in Figs. 4, 5 and 6 the entire shank 32 is formed as one piece swivelled to the guard 34 as indicated at 36 and formed 90 with the outer screw threads 38 for receiving the outer plate 40. The guard 34 shown in Figs. 4 to 6 is formed with a usual comb edge 50. The devices for movably and piv- 95 otally supporting the plate 40 upon the guard 34 according to this form of the invention comprise the side plate 42 slotted as indicated at 44 and received on the transverse pin 46 supported upon the side lugs 48 formed directly on the guard 34.

- The movement of the plate 16 or 40 with respect to the guard is clearly indicated in Figs. 2 and 6. It will be understood that a certain movement of the plate on a right line 5 toward or from the guard is necessary, according to the disclosure herein, due to the flexing of the blade about the arc of the outer surface of the guard. Such movement avoids displacing the blade when the plate is moved 10 toward the assembled blade and guard. Furthermore this right line movement of the plate with respect to the guard allows accurate threading of the stud 20 or 38 into the threaded aperture of the outer plate.
- 15 The use of the razor will be readily apparent from the above description.

Having now described my invention what I claim and desire to secure by Letters Patent is:

- 20 A safety razor including, in combination, a handle, a guard, studs mounted upon said guard and projecting upwardly therefrom, a clamping plate for association with said guard, said plate being formed with holes 25 for the reception of said studs, a rod for engaging said clamping plate and slidably within said handle, a circular slot formed in said rod near the plate engaging end thereof, a pin projecting inwardly from said handle 30 and riding within said slot to limit the sliding movement of said rod, downwardly extending side arms forming a part of said plate, said arms having slots at their lower ends, and means carried by said handle and 35 extending through said last-named slots for engaging said arms whereby the movement of said clamping plate with respect to said guard is limited.

Signed at New York, in the county of New 40 York and State of New York, this 18th day of December, A. D. 1928.

HYMAN R. SEGAL.
